UNITED STATES PATENT OFFICE.

PETER ROBERTS, OF NEW YORK, N. Y.

CAPSTAN.

Specification of Letters Patent No. 8,746, dated February 17, 1852.

To all whom it may concern:

Be it known that I, PETER ROBERTS, of the city, county, and State of New York, have invented a new and Improved Method or 5 Arrangement of Constructing the Machine known by the name of "Capstan" or "Heaver," as commonly used on shipboard; and I do hereby declare that the following is a full and exact description thereof, reference being had to the accompanying drawings and to the letters of reference marked thereon.

The nature of my invention, consists of a new combination of mechanical elements, 15 arranged within the base of a machine, known by the following names, viz, capstan, windlass or heaver, as commonly used on ship board; the object of which arrangement, is the continuous winding motion of 20 that part called the head, (upon which the rope or chain is wound) while the levers, or heavers, are caused to move alternately backward and forward.

In order therefore to enable others 25 skilled in the art to make and use my invention, I will proceed to describe its construction and operation.

In the drawings accompanying this description, at A, Figure 1, is shown in section 30 the main head, and at B, is shown in section, the box or base of the capstan, with the upright shaft C, (of wrought iron) and firmly secured to the base B. Upon this upright shaft is supported the main head A, and 35 upon which shaft the main head, can revolve freely; the head, being secured from a lifting action (caused by the pawls M M,) by means of the circular plate marked I, which plate is composed of two semi-circular 40 parts as shown at I, for the purpose of putting it on to the head of the shaft C, this plate being secured to the arms of the main head, by means of four screw bolts, (two in either half) two of which are shown 45 in section, near I. Within the base or box B, is contained the improved parts, by means of which the winding motion of the main head is made continuous.

At S, S, in the section Fig. 1, is shown 50 an end view of two shafts; (the same shafts are shown in part at S, S, Fig. 1, plan view.) Upon those two shafts are placed segments of four cog-wheels E E E E, as shown in plan and section Fig. 3, which I 55 shall denominate tumblers; upon those four tumblers rests the piece marked D, and which

I shall denominate the slide. This slide is shown at D D, in plan and section Fig. 3, and being composed of a plate of cast iron, and having an opening in its center and 60 through which the upright shaft C, shown in Fig. 1, passes; the opening in the center being sufficiently large to allow the slide D, to move alternately backward and forward—motion being imparted to this slide 65 by a vibrating motion of the four tumblers upon which the slide rests; this slide having cogs, upon its upper and lower surfaces, arranged in right lines as shown in the plan Fig. 3, one row of which is represented 70 by dotted lines, indicating, that they are located on the under surface of the slide, those cogs being cast in one piece with the slide, there being four rows of cogs, upon the same slide two of which, hang or project downward, and gear into the four tumblers as 75 shown at E, E, and H, in Fig. 3, the other two rows of cogs, upon the slide, are turned inward and gear into the two wheels marked P, and Q, as shown in section Fig. 1, and 80 by plan in Fig. 4, together with a detached portion of the slide containing the cogs, and where the wheel P, is represented as above the slide D, and having its cogs upon its lower surface, while the wheel Q, is 85 represented as having its cogs upon its upper surface. In the plan Fig. 3, is shown upon the slide D, the relative position of the two wheels P, and Q, by a dotted line, as also the cogs upon the slide D, and in 90 section at D, as shown by the witness marks thus >.

At G—G, in Fig. 3, is shown by plan and section a ratchet wheel of peculiar construction; this wheel, having an elongated hub 95 or tube, cast with the wheel in one piece; this ratchet wheel, being adjusted upon the upright shaft C, as shown at G, in section Fig. 1, in its working position, and being at liberty to revolve upon the shaft quite 100 freely; the hub of this wheel G, serves as a shaft for the two wheels P, and Q, as shown in section Fig. 1, and upon which they severally revolve or vibrate, a portion of a revolution at each motion of the levers. Detached portions, of the upper surfaces of the two wheels G, and P, are shown in their relative positions in plan view Fig. 1, as having the upper works removed.

At N N, in section Fig. 1, are shown two 110 pawls, and represented as being attached to the wheel Q and fallen into the teeth of the

ratchet wheel G, and in their working position. At M—M, in section Fig. 1, are likewise shown two pawls represented, as being attached to the lower arms of the main head 5 A, and fallen into the teeth of the ratchet wheel P, and also in their working order. The two shafts S, S, are shown in part near B, in the plan Fig. 1, and in their proper places and having one of the tumblers E, 10 adjusted upon each in its proper place the upper works being removed.

At H H, in Fig. 3, is shown a side view of the slide D, and at H, resting upon the two tumblers E E, in their working position. 15 The sockets F F, upon the shaft S, in section Fig. 3, (one of which is shown at F, with the lever or heaver in its place and broken off) likewise, two of the sockets and levers being shown in elevation at F, in Fig. 2, 20 there being four levers in all.

The cover of the base marked O, the ratchet L, upon its upper surface (and pawls for the same) the main head A, and its cover J, are severally sockets, covers, head, 25 &c., of the ordinary kind now in use, and therefore need no particular description.

From the previous description, it will be understood that the whole apparatus is operated by a vibrating motion of the levers 30 F F, shown in elevation Fig. 2, there being four, two on either side, now therefore it will be seen, that when the levers are in the position indicated in the elevation Fig. 2, that the slide D, has been moved in one direction to the extremity that it is intended 35 to be moved, and that in its motion thus, it has carried or turned the wheel P, in one direction, and the wheel Q, in the contrary direction, and that in turning the 40 wheel Q, the ratchet wheel G, (by the action of the pawls N N,) must of necessity be turned in the same direction as Q, and the main head A, being made fast upon the upper end of the hub of the ratchet wheel G, 45 it is turned in the same direction; during

which operation, the two pawls marked M M, and attached to the arms of the main head, are carried with it while the wheel marked P, is turned in the contrary direction. Upon reversing the levers it will be 50 seen that the slide D, will be moved in a contrary direction, and that in its course it turns the wheel P, in a contrary direction from what it was turned by the first motion of the levers, and that the wheel P, (by the 55 action of the pawls M M,) turns the main head, in the same direction as it was turned by the first motion of the levers, and that in so turning, it of necessity turns the wheel G, along with it while the wheel Q, is turned 60 in the contrary direction from the wheel G, and the two pawls N N, are carried by the wheel Q, to a new place in the teeth of the wheel G and are therefore ready to perform a second operation similar to the first. The 65 pawls outside upon the main head acting momentarily to sustain the main head during the momentary stoppage of the levers while being changed from one direction to the other.

The combined parts as set forth in the previous description, when operated as herein shown, serves to keep the winding motion of the main head of the capstan continuous.

What I claim as my invention, and desire 75 to secure by Letters Patent, is—

The combination of the following mechanical elements, viz, the vibrating tumblers acted upon by handspikes; the slide D, with its racks; the cog wheels P, and Q, the 80 former formed also with ratchet teeth; the ratchet wheel G, and its hollow shaft; the pawls M, and N, the whole arranged within the base B, and with respect to each other, and acting substantially as described.

PETER ROBERTS.
